DESIGN FOR A SHINGLE ROOF OR LIKE ARTICLE

Norman P. Harshberger, Scarsdale, N. Y., assignor to Bakelite Building Products Co. Inc., New York, N. Y., a corporation of Delaware

Application January 9, 1934, Serial No. 50,361

Term of patent 14 years

To all whom it may concern:

Be it known that I, Norman P. Harshberger, a citizen of the United States, residing at Scarsdale, in the county of Westchester and State of New York, have invented a new, original, and ornamental Design for Shingle Roof or like Article, of which the following is a specification, reference being made to the accompanying drawing, forming part thereof.

Fig. 1 shows a fragmentary portion of the de-

sign for the shingle roof illustrated in Fig. 2, and Fig. 2 is a plan view of a section of the shingle roof of the new design.

The dominant feature of the present invention consists of the staggered arrangement of the cross-like elements shown in Fig. 2.

I claim:

The ornamental design for a shingle roof or like article substantially as shown and described.

NORMAN P. HARSHBERGER.
